[57] **ABSTRACT**

5-(Oxo, thio or imino)-7,8-dihydro[1,4]diazepino[7,1-*a*] isoquinolines, lower alkylenolethers, the N-oxide, quaternaries or salts thereof are neuroleptic agents.

4 Claims, No Drawings

DIAZEPINOISOQUINOLINES

SUMMARY OF THE INVENTION

The present invention concerns and has for its object the provision of new 5-(oxo, thio or imino)-7,8-dihydro[1,4]diazepino[7,1-*a*]isoquinolines, preferably of those corresponding to Formula I

wherein Ph is a 1,2-phenylene group, each of R₁, R₃ and R₄ is hydrogen or lower alkyl or R₃ and R₄ together are lower alkylene or alkenylene, R₂ is hydrogen, lower alkyl, alkenyl, iso- or heterocyclic aryl or aralkyl, X is oxo, thio or imino and alk is lower alkylene separating Ph from N by two carbon atoms, or of 5-lower alkyleneethers, the N-oxide, lower alkyl quaternaries or pharmaceutically useful acid addition salts thereof, as well as of corresponding pharmaceutical compositions and methods for the preparation or application of said products, which are useful neuroleptic and anticonvulsive agents.

DESCRIPTION OF THE PREFERRED EMBODIMENTS

In the above compounds of Formula I, the 1,2-phenylene group Ph is unsubstituted or substituted, by one or more than one, preferably up to three, advantageously up to two, members selected from the group consisting of lower alkyl, e.g. methyl, ethyl, n- or i-propyl or -butyl, free, etherified or esterified hydroxy, such as lower alkoxy, alkyleneoxy, aralkoxy, alkanoyloxy or halogeno, e.g. methoxy, ethoxy, n- or i-propoxy or -butoxy; methyleneoxy, 1,1- or 1,2-ethylenedioxy or 2,2-propylenedioxy; benzyloxy; acetoxy, propionyloxy or pivalyloxy; fluoro, chloro or bromo; trifluoromethyl; or tert. amino, such as di-lower alkylamino, e.g. dimethylamino or diethylamino. The term "lower," referred to above or hereinafter in connection with organic radicals or compounds respectively, defines such with up to seven, preferably up to four carbon atoms.

A lower alkyl group R₁, R₂, R₃ or R₄ is such illustrated above, but also tert. butyl, n- or i-pentyl, -hexyl or -heptyl. A lower alkenyl group R₂ is, for example, allyl or methallyl. A lower alkylene or alkenylene group R₃ + R₄ is preferably such forming a three to seven membered spiro-ring, e.g. ethylene, 1,2- or 1,3-propylene, 1,2-, 1,3-, 2,3- or 1,4-butylene, 1,4- or 1,5-pentylene or -hexylene; 1,4-but-2-enylene or 1,5-pent-2-enylene.

An isocyclic aryl or aralkyl group is preferably that of the formula H—Ph—C_mH_{2m}—, wherein Ph has the meaning given above and m is an integer from 0 to 4. A heterocyclic aryl or aralkyl group is preferably that of the formula Hc—C_mH_{2m}, wherein m has the previous meaning and Hc is a pyridyl, furyl or thienyl group, either unsubstituted or substituted by up to three lower alkyl, preferably methyl groups, e.g. 2-, 3- or 4-(pyridyl or pyridylmethyl), 2- or 3-(furyl or furfuryl), 2- or 3-(thienyl or phenyl).

The lower alkylene group alk is preferably ethylene, but also 1,2-propylene, 1,2- or 2,3-butylene or -pentylene.

The compounds of the invention exhibit valuable pharmacological properties. Primarily they show neuroleptic and anticonvulsive effects and cause a central adrenergic neuron blockade, particularly in the brain stem. This can be demonstrated in animal tests, using advantageously mammals, such as mice, rats or monkeys, as test objects. The compounds of the invention can be applied to the animals enterally or parenterally, e.g. orally or intraperitoneally, for example, in the form of aqueous solutions or starchy suspensions. The dosage may range between about 0.1 and 200 mg/kg/day, preferably between about 1 and 50 mg/kg/day. Having administered the compounds of the invention to the test animals, for example, up to 10 mg/kg/day p.o. to rats, they increase norepinephrine concentration in their brain stem and selectively decrease its turnover rate therein. When administered up to 50 mg/kg/day p.o. to squirrel monkeys, they decrease their lever-pressing avoidance responses, i.e., the number of electric shocks taken by the animals increases with the dose applied (Sidman procedure). For example, said effects can be observed with the 2-(3,4-methylenedioxyphenyl)-10,11-dimethoxy-7,8-dihydro[1,4]diazepino[7,1-*a*]isoquinolin-5(4H)-one, its hydrochloride or d,l-4-methyl derivative, characteristic compounds of the invention, down to a p.o. dose of 2.5 mg/kg/day in rats or 20 mg/kg/day p.o. in squirrel monkeys. Accordingly, the compounds of the invention are useful as neuroleptic and anticonvulsive agents, or as intermediates in the preparation of other valuable compositions of matter, especially of pharmaceutically useful products.

Preferred compounds of the invention are those of Formula I, in which Ph is 1,2-phenylene (lower alkyl)_n-1,2-phenylene, (hydroxy)_n-1,2-phenylene, (lower alkoxy)_n-1,2-phenylene, (lower alkyleneoxy)-1,2-phenylene, (lower alkanoyloxy)_n-1,2-phenylene, (halogeno)_n-1,2-phenylene, (trifluoromethyl)-1,2-phenylene or (di-lower alkylamino)-1,2-phenylene, wherein n is an integer from 1 to 3, (preferably 1 or 2), each of R₁, R₃ and R₄ is hydrogen or lower alkyl, or R₃ and R₄ together are lower alkylene or alkenylene forming a three to seven membered spiro-ring, R₂ is hydrogen, lower alkyl, H—Ph—C_mH_{2m} or Hc—C_mH_{2m}, wherein Ph has the meaning in this paragraph, Hc is pyridyl, (lower alkyl)_n-pyridyl, furyl, (lower alkyl)_n-furyl, thienyl or (lower alkyl)_n-thienyl, n is said integer from 1 to 3 and m is an integer from 0 to 4, X is oxo, thio or imino and alk is lower alkylene separating Ph from N by two carbon atoms, a 5-lower alkyleneether, the N-oxide, lower alkyl quaternaries or pharmaceutically useful acid addition salts thereof.

Outstanding are the compounds of Formula II

wherein each of R₅ and R₆ is hydrogen, lower alkyl, lower alkoxy or halogen, or both R₅ and R₆ are lower

alkylenedioxy, R_7 is phenyl, (lower alkyl) $_n$ -phenyl, (lower alkoxy) $_n$ -phenyl, (lower alkylendioxy)-phenyl, (halogeno) $_n$ -phenyl, (trifluoromethyl)-phenyl, pyridyl, (lower alkyl) $_n$ -pyridyl, furyl, (lower alkyl) $_n$ -furyl, thieryl or (lower alkyl) $_n$ -thienyl, n is an integer from 1 to 3, and R_8 is hydrogen or lower alkyl, or pharmaceutically useful acid addition salts thereof.

Most preferred are those compounds of Formula II, wherein each of R_5 and R_6 is hydrogen or methoxy, R_7 is phenyl, tolyl, (methoxy) $_n$ -phenyl, (methylenedioxy)-phenyl, (fluoro)-phenyl, (chloro)-phenyl, (trifluoromethyl)-phenyl or thiienyl, n is an integer from 1 to 3, and R_8 is hydrogen or alkyl with up to four carbon atoms, or pharmaceutically useful acid addition salts thereof.

The compounds of the invention are prepared according to known methods. For example, the process for their preparation consists in reacting a 1-(2-iminoethylidene)-1,2,3,4-tetrahydroisoquinoline of Formula III

with an α -amino-(alkane, cycloalkane or cycloalkene)-carboxylic or thiocarboxylic acid ester, the nitrile or an acid addition salt thereof and, if desired, converting any resulting compound into another compound of the invention.

Said ester is advantageously a lower alkyl, e.g. the methyl or ethyl, ester or thioester. Depending on the sulfur- or nitrogen content of said carboxylic acid derivatives, compounds of Formula I are obtained, wherein X is thio or imino.

The above process is carried out according to standard methods, for example in the presence or absence of diluents, preferably such as are inert to the reagents and are solvents thereof, of catalysts, condensing agents and/or inert atmospheres, such as nitrogen, at temperatures equal to or advantageously higher than room temperature, at atmospheric or superatmospheric pressure. Condensing agents are either acids or bases, for example, mineral acids, e.g. hydrohalic acids, nitrogen bases or alkalis respectively, preferably tert. amines, such as pyridine, or alkali metal hydroxides or lower alkoxides, e.g. sodium hydroxide, methoxide or ethoxide.

The compounds of the invention so obtained can be converted into each other according to known methods. For example, resulting oxo-compounds can be converted into thio-compounds or vice versa, e.g. by treating the former with sulfur or sulfurization agents, such as phosphorus pentasulfide, or treating the latter with desulfurization agents, such as lead or mercury oxide. Resulting aralkoxy, e.g. benzyloxy compounds can be hydrogenolyzed, for example, with the use of catalytically activated hydrogen, e.g. hydrogen in the presence of palladium catalysts. Resulting phenols can be etherified or esterified, for example, with the use of reactive derivatives of corresponding alcohols or acids, such as lower alkyl halides, sulfates or sulfonates, e.g. methyl or ethyl iodide, sulfate or p-toluenesulfonate; or lower alkanoic acid halides or anhydrides, e.g. acetyl

chloride or acetanhydride. Analogously the lower alkyl quaternaries or 5-lower alkylenolethers are obtained by reacting resulting compounds either directly with said derivatives of lower alkanols, or resulting 5-oxo compounds with phosphorus halides or oxyhalides, e.g. phosphorus pentachloride or oxychloride first, and subsequently with alkali metal lower alkoxides or -sulfides, e.g. those mentioned above, or sodium methyl- or ethylsulfide, to yield said enol ethers.

The compounds of the invention are obtained in the free form or in the form of their acid addition salts, depending on the conditions under which the process is carried out. Salts that are obtained can be converted into the free bases in known manner, for example, with

alkalies or ion exchangers. Free bases that are obtained can be converted into salts by reaction with inorganic or organic acids, especially those that are suitable for the formation of therapeutically useful acid addition salts. Such acids are inorganic or organic acids, for ex-

ample, mineral acids, such as hydrohalic acids, e.g. hydrochloric or hydrobromic acid; sulfuric, phosphoric, nitric or perchloric acid, or aliphatic, alicyclic, araliphatic, aromatic or heterocyclic carboxylic or sulfonic acids, such as formic, acetic, propionic, succinic, gly-

collic, lactic, malic, tartaric, citric, ascorbic, maleic, hydroxymaleic, pyroracemic, phenylacetic, benzoic, aminobenzoic, anthranilic, 4-hydroxybenzoic, salicylic, 4-aminosalicylic, embonic, nicotinic, methanesulfonic, ethanesulfonic, hydroxyethanesulfonic, ethylenesul-

fonic, halobenzenesulfonic, toluenesulfonic, naphthalenesulfonic, sulfanilic or cyclohexylsulfamic acid; methionine, tryptophan, lysine or arginine. These or other salts, for example, the picrates, can also be used in the purification of the free compounds. In view of the close relationship between the salts and the free compounds, whenever such are referred to in this context, a corresponding salt is also intended, provided such is possible or appropriate under the circumstances.

Resulting mixtures of isomers can be separated into the single isomers by methods in themselves known, e.g. by fractional distillation, crystallization and/or chromatography. Racemic products can likewise be resolved into the optical antipodes, for example, by separation of diastereomeric salts thereof, e.g. by the fractional crystallization of d- or L-tartrates.

The invention further includes any variant of the present process, in which an intermediate product obtainable at any stage of the process is used as starting material and any remaining steps are carried out, or the process is discontinued at any stage thereof, or in which the starting materials are formed under the reaction conditions, or in which the reaction components are used in the form of their salts. Thus, for example, when using acidic condensing agents, which can be reagents also, such as salts, e.g. glycine ethyl ester hydrochloride, the primary condensation product is that of Formula IV

wherein R is preferably lower alkyl. Upon treatment with bases (which again can be reagents), said compounds ring-close to those of Formula I. Also, the above phenols can be used in the form of their alkali metal, e.g. sodium salts. Mainly such starting materials should be used in the reactions of the invention that lead to the formation of those compounds indicated above as being specially valuable.

The starting material used can be prepared by methods known per se, for example, by reacting a 1-alkyl-3,4-dihydroisoquinoline of Formula V

(prepared according to the Bischler-Napieralski reaction) with an alkali metal amide, such as a lithium di-lower alkylamide, e.g. lithium-diisopropylamide, condensing the resulting metal compound with a reactive functional derivative of the acid $R_2\text{-COOH}$, such as a lower alkyl ester, iminoester, N-lower alkylated imino-ester or the nitrile thereof, and converting any resulting 1-(2-oxoethylidene)-1,2,3,4-tetrahydroisoquinoline into the corresponding imino compound of Formula III, for example, by reacting said carbonyl derivative (vinylogous amide) with a halogenating or esterifying agent, such as a phosphorus halide or oxyhalide, or an acidified lower alkanol, e.g. ethanolic hydrogen chloride, and reacting the resulting vinylogous amidhalide or imino ester with ammonia. Said compounds of Formula III and their oxoprecursors, are not only new and valuable starting materials or intermediates respectively, but also pharmacologically active compounds, which exhibit tranquilizing, muscle relaxing and analgesic effects.

The pharmacologically active compounds of the invention are useful in the manufacture of pharmaceutical compositions comprising an effective amount thereof in conjunction or admixture with excipients suitable for either enteral or parenteral application. Preferred are tablets and gelatin capsules comprising the active ingredient together with (a) diluents, e.g. lactose, dextrose, sucrose, mannitol, sorbitol, cellulose and/or glycine, (b) lubricants, e.g. silica, talcum, stearic acid, its magnesium or calcium salt and/or polyethylene glycol, for tablets also (c) binders, e.g. magnesium aluminum silicate, starch paste, gelatin, tragacanth, methylcellulose, sodium carboxymethylcellulose and/or polyvinylpyrrolidone, if desired, (d) disintegrants, e.g. starches, agar, alginic acid or its sodium salt, enzymes of the binders or effervescent mixtures and/or (e) adsorbents, colorants, flavors and sweeteners. Injectable compositions are preferably aqueous isotonic solutions or suspensions, and suppositories are advantageously fatty emulsions or suspensions. They may be sterilized and/or contain adjuvants, such as preserving stabilizing wetting or emulsifying agents, solution promoters, salts for regulating the osmotic pressure and/or buffers. Said pharmaceutical compositions may also contain other therapeutically valuable substances. They are prepared according to conventional mixing, granulating or coating methods respectively

and contain about 0.1 to 75 percent, preferably about 1 to 50 percent, of the active ingredient.

The following examples are intended to illustrate the invention and are not to be construed as being limitations thereon. Temperatures are given in degrees Centigrade, and all parts wherever given are parts by weight.

EXAMPLE 1

The mixture of 7.3 g of 1-[2-imino-2-(3,4-methylenedioxyphenyl)-ethylidene]-1,2,3,4-tetrahydroisoquinoline, 17.5 g of glycine ethyl ester hydrochloride and 80 ml of anhydrous ethanol is refluxed for 3 hours and evaporated under reduced pressure. The residue is taken up in methylene chloride, the solution washed with cold 5 percent aqueous sodium hydroxide, dried and evaporated, to yield the N-[1-(3,4-methylenedioxyphenyl)-2-(1,2,3,4-tetrahydro-1-isoquinolylidene)-glycine ethyl ester. It is taken up in 80 ml of anhydrous ethanol, 25 ml of N-ethanolic sodium ethylate are added and the mixture stirred for 16 hours at room temperature. It is evaporated under reduced pressure, the residue taken up in methylene chloride, the solution washed with aqueous sodium bicarbonate, dried, evaporated and the residue chromatographed on 25 g of silica gel. The column is eluted with chloroform, the eluate evaporated and the residue triturated with petrolether, to yield the 2-(3,4-methylenedioxyphenyl)-7,8-dihydro[1,4-]diazepino[7,1-*a*]isoquinolin-5(4H)-one of the formula

NMR (CDCl_3): $\delta = 2.9, 3.9, 4.45, 5.95$ and $6.7-7.8$ ppm.

The starting material is prepared as follows: The mixture of 50 g of N-phenethyl-acetamide and 500 g of polyphosphoric acid is stirred at $200^\circ-205^\circ$ for 3 hours. It is poured into 2 kg of crushed ice, the solution made basic with 30 percent aqueous sodium hydroxide while cooling and extracted with methylene chloride. The extract is dried, evaporated and the residue taken up in 600 ml of diethyl ether. The solution is cooled with ice, 4 ml of acetyl chloride are slowly added, the mixture stirred for 15 minutes, combined with some crushed ice and washed twice with 250 ml of N hydrochloric acid. The aqueous solution is made basic with 30 percent aqueous sodium hydroxide and extracted with methylene chloride. The extract is dried, evaporated, the residue distilled and the fraction boiling at $114^\circ-115^\circ/12$ mm Hg collected, to yield the 1-methyl-3,4-dihydroisoquinoline.

The solution of 14.52 g thereof in 100 ml of diethyl ether is added dropwise to the mixture prepared from 14.2 ml of diisopropylamine in 100 ml of diethyl ether and 62 ml of 1.6N butyl lithium in hexane, while stirring at -20° to -30° under nitrogen. After $\frac{1}{2}$ hour the

mixture is cooled to -70° and the solution of 14.7 g of 3,4-methylenedioxybenzonitrile in 120 ml of diethyl ether is added dropwise. After stirring overnight, it is diluted with diethyl ether, washed with water, dried and evaporated. The residue is heated at $125^{\circ}/0.1$ mm Hg to remove starting material, and the resulting 1-[2-imino-2-(3,4-methylenedioxyphenyl)-ethylidene]-1,2,3,4-tetrahydroisoquinoline, melting at $105^{\circ}-107^{\circ}$, used as such.

EXAMPLE 2

The mixture of 6.5 g of 1-[2-imino-2-(3,4,5-trimethoxyphenyl)-ethylidene]-6,7-dimethoxy-1,2,3,4-tetrahydroisoquinoline, 11.4 g of glycine ethyl ester hydrochloride and 50 ml anhydrous ethanol is refluxed for 2 $\frac{1}{2}$ hours and evaporated under reduced pressure. The residue is taken up in methylene chloride, the solution washed with cold 5 percent aqueous sodium hydroxide, dried and evaporated. The residue is taken up in diethyl ether, the solution clarified with charcoal, filtered and evaporated, to yield the N-[1-(3,4,5-trimethoxyphenyl)-2-(6,7-dimethoxy-1,2,3,4-tetrahydro-1-isoquinolylidene)-ethylidene]-glycine ethyl ester, melting at $138^{\circ}-140^{\circ}$. It is taken up in 80 ml of anhydrous ethanol, the solution combined with 13.5 ml of 1.1 N methanolic sodium methylate and the mixture stirred for 16 hours at room temperature. It is evaporated under reduced pressure, the residue taken up in methylene chloride, the solution washed with aqueous sodium bicarbonate, dried, evaporated and the residue recrystallized from ethanoldiethyl ether, to yield the 2-(3,4,5-trimethoxyphenyl)-10,11-dimethoxy-7,8-dihydro[1,4]diazepino[7,1-*a*]isoquinolin-5(4H)-one, melting at $214^{\circ}-215^{\circ}$. The hydrochloride thereof is obtained from a concentrated ethanolic solution of the base, which is acidified with ethanolic hydrogen chloride; it melts at $237^{\circ}-238^{\circ}$.

The starting material is prepared as follows: To the stirred mixture of 53.7 g of 3,4-dimethoxyphenethylamine, 700 ml of methylene chloride and 50 ml of triethylamine, the solution of 23.4 g of acetyl chloride in 500 ml of methylene chloride is added dropwise. After stirring the mixture for 2 hours, water and sodium carbonate is added, the organic layer separated, dried and evaporated, to yield the N-3,4-dimethoxyphenethylacetamide, melting at $96^{\circ}-97^{\circ}$.

43 g thereof are dissolved in 1.45 lt of a chloroform-diethyl ether solution, containing 300 mg polyphosphoric acid ethyl ester per ml and the mixture is evaporated under reduced pressure. The residue is stirred at $120^{\circ}-125^{\circ}$ for 70 minutes, cooled and combined with crushed ice. The solution obtained is washed with ethyl acetate, adjusted with 30 percent aqueous sodium hydroxide to pH = 10 and extracted with chloroform. The extract is dried, evaporated and the residue recrystallized from diethyl ether, to yield the 1-methyl-6,7-dimethoxy-3,4-dihydroisoquinoline melting at $101^{\circ}-102^{\circ}$.

The solution of 5.12 g thereof in 25 ml of tetrahydrofuran is added dropwise to the mixture prepared from 3.55 ml of diisopropylamine in 25 ml of diethyl ether and 15.5 ml of 1.6N butyl lithium in hexane under nitrogen at -30° . After completed addition the mixture is stirred and allowed to warm up to room temperature. Thereupon, it is cooled to -70° and combined with the solution of 4.83 g of 3,4,5-trimethoxybenzonitrile in 25 ml of tetrahydrofuran. The mixture is allowed to warm

up to room temperature and stirred overnight. It is then cooled to 0° , water and diethyl ether are added and the organic layer separated. The aqueous solution is extracted with diethyl ether, the combined organic solutions dried, evaporated and the residue recrystallized from diethyl ether, to yield the 1-[2-imino-2-(3,4,5-trimethoxyphenyl)-ethylidene]-6,7-dimethoxy-1,2,3,4-tetrahydroisoquinoline melting at $142^{\circ}-144^{\circ}$.

The hydrochloride thereof, prepared from its concentrated ethanolic solution by neutralization with ethereal hydrogen chloride, melts at $239^{\circ}-240^{\circ}$.

By replacing in the above procedure the 3,4,5-trimethoxybenzonitrile by the equivalent amount of methyl 3,4,5-trimethoxybenzoate, the tetrahydrofuran by three times the volume of diethyl ether and the water by 2N hydrochloric acid to reach the pH = 4, the 1-[2-oxo-2-(3,4,5-trimethoxyphenyl)-ethylidene]-6,7-dimethoxy-1,2,3,4-tetrahydroisoquinoline is obtained melting at $114^{\circ}-115^{\circ}$. (It can also be obtained by hydrolysing 15 g of the former imino compound in 330 ml of methylene chloride with 150 ml of N hydrochloric acid at room temperature for 2 hours while stirring. The pH of the mixture is adjusted to 8 with sodium hydroxide and carbonate, the organic solution separated, dried, evaporated and the residue recrystallized from diethyl ether.)

The mixture of 0.8 g thereof, 10 ml of toluene and 0.43 g of phosphorus pentachloride is heated to 110° for $\frac{1}{2}$ hour and evaporated under reduced pressure, to yield the corresponding vinylogous amidchloride. It is taken up in 30 ml of methylene chloride saturated with ammonia and the mixture stirred for 2 days at room temperature. It is washed with 0.1N aqueous sodium hydroxide, dried and evaporated, to yield the 1-[2-imino-2-(3,4,5-trimethoxyphenyl)-ethylidene]-6,7-dimethoxy-1,2,3,4-tetrahydroisoquinoline.

The same compound is obtained by stirring 1.2 g of the vinylogous amide with 30 ml of saturated ethanolic hydrogen chloride for 2 days at room temperature, evaporating the mixture and stirring the residual vinylogous imino-ethyl ester with 30 ml of methylene chloride-ammonia for 3 days and working up the mixture as described above.

EXAMPLE 3

The mixture of 4.2 g of 1-[2-imino-2-(3,4-methylenedioxyphenyl)-ethylidene]-6,7-dimethoxy-1,2,3,4-tetrahydroisoquinoline, 8.4 g of glycine ethyl ester hydrochloride and 82 ml of anhydrous ethanol is refluxed for 1 $\frac{1}{2}$ hours and evaporated under reduced pressure. The residue is taken up in chloroform, the solution washed with ice cold 5 percent aqueous sodium hydroxide, dried and evaporated, to yield the N-[1-(3,4-methylenedioxyphenyl)-2-(6,7-dimethoxy-1,2,3,4-tetrahydro-1-isoquinolylidene)-ethylidene]-glycine ethyl ester. It is taken up in 60 ml of anhydrous ethanol, 13.2 ml of N-ethanolic sodium ethylate are added and the mixture stirred for 16 hours at room temperature. It is evaporated under reduced pressure, the residue taken up in chloroform, the solution washed with aqueous sodium bicarbonate, dried, evaporated and the residue recrystallized from ethanol, to yield the 2-(3,4-methylenedioxyphenyl)-10,11-dimethoxy-7,8-dihydro[1,4]diazepino[7,1-*a*]isoquinolin-5(4H)-one, melting at $214^{\circ}-215^{\circ}$; the hydrochloride thereof melts at $188^{\circ}-190^{\circ}$ (ethanol).

The starting material is prepared as follows: To the solution of 10.7 ml of diisopropylamine in 75 ml of diethyl ether, 47 ml of 1.6 N butyl lithium in hexane are added while stirring at -20° under nitrogen. Thereupon the solution of 15.5 g of 1-methyl-6,7-dimethoxy-3,4-dihydroisoquinoline in 100 ml of tetrahydrofuran is added while stirring at -45°. After completed addition, the mixture is stirred and allowed to warm up to room temperature, whereupon it is cooled to -70° and combined with the solution of 11.1 g of 3,4-methylenedioxobenzonitrile in 75 ml of tetrahydrofuran. The mixture is allowed to warm up to room temperature and stirred for 16 hours. It is combined with crushed ice, the organic layer separated and the aqueous solution extracted with methylene chloride. The combined organic solutions are dried, evaporated and the residue recrystallized from diethyl ether, to yield the 1-[2-imino-2-(3,4-methylenedioxophenyl)-ethylidene]-6,7-dimethoxy-1,2,3,4-tetrahydroisoquinoline, melting at 175°-176°.

EXAMPLE 4

3.5 g of 1-[2-imino-2-(3,4-methylenedioxophenyl)-ethylidene]-6,7-dimethoxy-1,2,3,4-tetrahydroisoquinoline, 7.7 g of d,l-alanine ethyl ester hydrochloride and 30 ml of anhydrous ethanol is refluxed for 12 hours and evaporated under reduced pressure. The residue is taken up in methylene chloride, the solution washed with ice cold 5 percent aqueous sodium hydroxide, dried and evaporated. The residue is triturated with methylene chloride, to yield Residue A and the mother liquor is combined with 60 ml of ethanol and 9 ml of 1.1 N methanolic sodium methylate and stirred for 16 hours at room temperature. It is evaporated under reduced pressure, the residue combined with Residue A and dissolved in methylene chloride. The solution is washed with aqueous sodium bicarbonate, dried, evaporated and recrystallized from

40

60

65

silica gel and eluted with chloroform. The eluate is extracted with 500 ml of 5 percent hydrochloric acid, the extract washed with benzene-ethyl acetate (1:1) and made basic with aqueous sodium hydroxide. The mixture is extracted with methylene chloride, the extract dried, evaporated, the residue taken up in acetone and the solution neutralized with ethereal hydrogen chloride, to yield the d,l-2-(3,4-methylenedioxophenyl)-4-ethyl-10,11-dimethoxy-7,8-dihydro[1,4]diazepino[7,1-a]isoquinolin-5(4H)-one hydrochloride, melting at 184°-187°.

10

EXAMPLE 6

The mixture of 5.07 g of 1-[2-imino-2-(3,4-methylenedioxophenyl)-ethylidene]-6,7-dimethoxy-1,2,3,4-tetrahydroisoquinoline, 7.9 g of d,l-valine ethyl ester hydrochloride and 72 ml of pyridine is refluxed for 44 hours under nitrogen and evaporated under reduced pressure. The residue is taken up in methylene chloride, the solution washed with aqueous sodium bicarbonate, dried and evaporated. The residue is chromatographed on 50 g of silica gel and eluted with chloroform. The eluate is evaporated, the residue taken up in 500 ml of 5 percent hydrochloric acid and the solution washed with benzene-ethyl acetate (1:1). It is made basic with aqueous sodium hydroxide, extracted with methylene chloride, the extract dried and evaporated. The residue is taken up in acetone and the solution neutralized with ethereal hydrogen chloride, to yield the d,l-2-(3,4-methylenedioxophenyl)-4-isopropyl-10,11-dimethoxy-7,8-dihydro[1,4]diazepino[7,1-a]isoquinolin-5(4H)-one hydrochloride, melting at 189°-193°.

EXAMPLE 7

Analogous to the method illustrated by the Examples 1 to 4, the following compounds of Formula II are prepared from equivalent amounts of the corresponding starting material of Formula III; R₈ = H:

No.	R ₅	+ R ₆	R ₇	m.p.°C base	recryst. from	m.p.°C HCl(A)	m.p.°C start III

A = ethanol, B = diethyl ether

methanol, to yield the d,l-2-(3,4-methylenedioxophenyl)-4-methyl-10,11-dimethoxy-7,8-dihydro[1,4]diazepino[7,1-a]isoquinolin-5(4H)-one, melting at 138°-140°. The hydrochloride thereof melts at 180°-181° (ethanol).

EXAMPLE 5

The mixture of 6 g of 1-[2-imino-2-(3,4-methylenedioxophenyl)-ethylidene]-6,7-dimethoxy-1,2,3,4-tetrahydroisoquinoline, 8.6 g of d,l- α -aminobutyric acid ethyl ester hydrochloride and 85 ml of anhydrous pyridine is refluxed for 22 hours under nitrogen and evaporated under reduced pressure. The residue is taken up in methylene chloride, the solution washed with aqueous sodium carbonate, dried and evaporated. The residue is chromatographed on 50 g of

2-(3,4-methylenedioxophenyl)-10,11-dimethoxy-7,8-dihydro[1,4]diazepino[7,1-a]isoquinolin-5(4H)-one hydrochloride 1,000.00 g
Lactose 2,535.00 g
Corn starch 125.00 g
Polyethylene glycol 6,000 150.00 g
Talcum powder 150.00 g
Magnesium stearate 40.00 g
Purified water q.s.

EXAMPLE 8

Preparation of 10,000 tablets each containing 100.0 mg of the active ingredient:

Formula:

2-(3,4-methylenedioxophenyl)-10,11-dimethoxy-7,8-dihydro[1,4]diazepino[7,1-a]isoquinolin-5(4H)-one hydrochloride 1,000.00 g
Lactose 2,535.00 g
Corn starch 125.00 g
Polyethylene glycol 6,000 150.00 g
Talcum powder 150.00 g
Magnesium stearate 40.00 g
Purified water q.s.

Procedure:

All the powders are passed through a screen with openings of 0.6 mm. Then the drug substance, lactose,

talcum, magnesium stearate and half of the starch are mixed in a suitable mixer. The other half of the starch is suspended in 65 ml of water and the suspension added to the boiling solution of the polyethylene glycol in 260 ml of water. The paste formed is added to the 5 powders which are granulated, if necessary, with an additional amount of water. The granulate is dried overnight at 35°, broken on a screen with 1.2 mm openings and compressed into tablets using concave punches with 10.3 mm diameter, upper bisected.

Analogously, tablets are prepared containing the same amount of any of the other compounds described in the previous examples.

EXAMPLE 9

The mixture of 3.26 g of 2-(3,4-methylenedioxyphenyl)-10,11-dimethoxy-7,8-dihydro[1,4]diazepino[7,1-*a*]isoquinolin-5(4H)-one, 1.85 g of phosphorus pentasulfide and 85 ml of pyridine is refluxed under nitrogen for 1 hour and evaporated under reduced pressure. The residue is taken up in methylene chloride, the solution washed with aqueous sodium bicarbonate, dried and evaporated. The residue is chromatographed on 23 g of silica gel and the column eluted with chloroform. The eluate is evaporated and the 2.4 g of residue crystallized from methylene chloride-diethyl ether, to yield the 2-(3,4-methylenedioxyphenyl)-10,11-dimethoxy-7,8-dihydro[1,4]diazepino[7,1-*a*]isoquinolin-5(4H)-thione melting at 182°-184°, its hydrochloride melts at 223°-226° (ethanol).

I claim:

1. A compound corresponding to the formula

10 wherein each of R₅ and R₆ is hydrogen, methyl, methoxy, or both R₅ and R₆ are methylenedioxy, R₇ is phenyl, (methyl)_n-phenyl, (methoxy)_n-phenyl, (methylenedioxy)-phenyl, (fluoro or chloro)_n-phenyl, (trifluoromethyl)-phenyl, thiienyl or (methyl)_n-thienyl, n is an integer from 1 to 3, and R₈ is hydrogen or alkyl with up to four carbon atoms, or pharmaceutically useful acid addition salts thereof.

15 2. A compound as claimed in claim 1, in which formula each of R₅ and R₆ is hydrogen or methoxy, R₇ is phenyl, 3,4,5-(methoxy)_n-phenyl, 3,4-(methylenedioxy)-phenyl, 4-(fluoro)-phenyl, 4-(chloro)-phenyl, or 2-thienyl, n is an integer from 1 to 3, and R₈ is hydrogen or alkyl with up to three carbon atoms, or pharmaceutically useful acid addition salts thereof.

20 3. A compound as claimed in claim 1 and being the 2-(3,4-methylenedioxyphenyl)-10,11-dimethoxy-7,8-dihydro[1,4]diazepino[7,1-*a*]isoquinolin-5(4H)-one, or a pharmaceutically useful acid addition salt thereof.

25 4. A compound as claimed in claim 1 and being the d,l-2-(3,4-methylenedioxyphenyl)-4-methyl-10,11-dimethoxy-7,8-dihydro[1,4]diazepino[7,1-*a*]isoquinolin-5(4H)-one or a pharmaceutically useful acid addition salt thereof.
